UNITED STATES PATENT OFFICE.

HARRY JUBBER, OF KENILWORTH, NEW JERSEY.

ICE CREEPER.

1,408,516.

Specification of Letters Patent. Patented Mar. 7, 1922.

Application filed April 7, 1920. Serial No. 371,834.

To all whom it may concern:

Be it known that I, HARRY JUBBER, a citizen of the United States, residing at Kenilworth, in the county of Union and State of New Jersey, have invented certain new and useful Improvements in Ice Creepers, of which the following is a specification, reference being had therein to the accompanying drawings, which form a part thereof.

10 My invention relates to ice creepers and more particularly to a type thereof adapted to be removably secured to the shoes of the wearer.

An ice creeper made in accordance with 15 my invention is not only so constructed as to be capable of being quickly and firmly secured below the sole of an ordinary shoe or boot so as to prevent likelihood of the wearer losing his balance through slight 20 slippage of the foot with relation to the creeper, but its construction is such that bent or blunted spikes may be quickly removed therefrom and replaced by fresh spikes so as to preserve the efficiency of the creeper 25 as well as permit an inexpensive production thereof.

Since the spikes are loosely mounted with 30 relation to their supporting plate, I preferably so construct the creeper as to avoid likelihood of injury to the sole of a shoe or boot as a result of pressure upon said spikes, which feature is particularly desirable when the creeper is used upon rubber soled shoes or boots.

35 The use of a protecting plate also has the advantage that it will retain the spikes in position when the creeper is removed from the boot or shoe when not in use, the two plates being so connected as to ordinarily 40 maintain a permanent relation thereof while permitting their separation in a manner to expose the heads of the spikes to facilitate the assembling of the spikes in the structure, or the removal of blunted or bent spikes 45 and the substitution of new spikes therefor.

The invention consists primarily in an ice creeper embodying therein a plate having a plurality of independently removable headed spikes projecting therethrough and 50 means whereby said plate may be removably secured below the sole of a shoe, and in such other novel features of construction and combination of parts as are hereinafter set forth and described, and more particularly pointed out in the claims hereto appended.

Referring to the drawings,

Fig. 1 is a side elevation of a shoe with an ice creeper made in accordance with my invention, secured thereto;

60 Fig. 2 is a bottom plan view thereof;

Fig. 3 is a side view of a creeper upon a larger scale removed from the shoe with the securing straps detached therefrom; and

Fig. 4 is a plan view thereof with the 65 protecting plate moved in relation to the spike plate, to permit access to the various studs.

Like letters refer to like parts throughout the several views.

In the embodiment of my invention shown in the drawings, I have shown a spike plate *a* having a plurality of openings therethrough adapted to receive headed spikes *b* which may be ordinary, short metal tacks. Extending rearwardly of the portion of the spike plate having said openings, I provide a reduced shank *c* of a length sufficient to extend under the shank of a shoe.

The plate *a* ordinarily is made of light 80 sheet metal stock so that the user may readily conform it to the underside of the shank of the shoe, and thus minimize any tendency of slippage of the spike plate forwardly of the shoe when the creeper is secured thereto. The enlarged end of the plate *a* has slits *d*—*d'* at opposite sides thereof, adapted to receive a strap *e* of leather, textile webbing, or any other desired material, the ends of this strap or 85 webbing being provided with adjustable securing means such as a skate or other buckle *e'* by means of which the shank *c* may be secured with relation to the boot or shoe. The strap *e* is of a length sufficient to pass 90 across the toe of the shoe, and thus hold the plate *a* firmly in position toward the forward part thereof.

The shank *c* is provided with slits *c'*—*c''* through which a strap or webbing *f*, similar 100 to the strap or webbing *e*, passes, said strap or webbing *f* being provided with adjustable securing means as a skate or other buckle *f'*, and being of a length to pass over the instep of the wearer and thus not only hold 105 said shank under the shank of the shoe, but check any tendency of the creeper in its entirety to move toward the heel of the wearer, with a resultant loss of balance.

While under normal conditions the sole 110 of the shoe, when the creeper is secured thereto, would hold the various spikes in the

projected position, notwithstanding their removability with relation to the plate *a*, I 5 preferably provide a shield plate *g* connected to the plate *a* in any manner which will permit it to be removed from engagement with the plate *a* in a manner to expose the heads of the spikes *b*.

The configuration of the plate *g* is similar to that of the plate *a*, and it has a shank *h* 10 corresponding with the shank *c* of the plate *a*. In the drawings the two plates *a* and *g* are shown as being pivotally connected at the forward ends thereof by means of a riveted pivot *i*.

15 The plate *g* has slits *g'*—*g*² therein, adapted to register with the slits *d'*—*d*² respectively, through which the webbing *e* may pass, the intermediate portion of this webbing extending across said plate *g* so as to 20 avoid the necessity for sewing, riveting or otherwise connecting said strip to the main body of the creeper.

The shank *h* has slits *h'*—*h*² therein similarly arranged to the slits *c'*—*c*² so as to permit the webbing *f* to pass therethrough and extend across said shank between said slits, in the same manner and for the same purpose as described in relation to the slits *g'*—*g*².

30 I also provide the plates *a* and *g* with registering openings *j*—*j'* through which a cotter pin may be passed so as to minimize any likelihood of the separation of the plates *a* and *g* when the device is not in use, although ordinarily the straps *e* and *f* would prevent such separation of said plates.

In assembling a creeper made as herein described, the plates *a*—*g* are moved about the pivot *i* until all of the openings in the 40 spike plate are exposed. A headed spike *b*, such as an ordinary small tack, is then placed in each opening with the head thereof engaging the face of the plate *a* presented towards the plate *g*. The plate *g* is then restored to its normal position with the slits *g'*—*g*², *h'*—*h*² registering with the slits *d'*—*d*², *c'*—*c*² respectively, and the cotter pin *k* is passed through the openings *j*—*j'* and upset so as to hold the plate *g* hard 50 against the heads of the spikes *b* and prevent any possible separation of the plates with a resultant tilting of the spikes, thus minimizing possibility of their being bent while the creeper is in use.

55 The straps or webbings *e*—*f* are then threaded through the proper slits in the plates *a*—*g* and thin shanks *c*—*h*.

When using the creeper, the plate *g* is 60 placed against the sole of the boot or shoe and the ends of the straps or webbings *e* and *f* connected by means of the buckles *e'*—*f'* respectively, and drawn sufficiently tight to hold the plates *a*—*g* firmly against the sole of, and cause the shanks *c*—*h* to con-

form to and hug the shank of, the boot or 65 shoe.

With both boots and shoes equipped with creepers made in accordance with my invention, slipping is impossible when the wearer is walking, and it is possible to even run 70 upon icy surfaces.

If the spikes become bent, blunted or broken, they may be removed and replaced by new spikes by disassembling the structure, and reassembling same in the manner 75 above described.

Creepers made in accordance with my invention may be cheaply produced and by using ordinary tacks for spikes, the user 80 may readily secure same for renewal purposes. If desired, however, special hardened spikes may be used.

It is not my intention to limit the invention to the detailed configuration and construction of parts shown in the drawings, 85 it being apparent that such may be varied without departing from the spirit and scope of the invention.

Having described the invention, what I 90 claim as new and desire to have protected by Letters Patent, is:—

1. An ice creeper embodying therein a plate, a plurality of independently removable, headed spikes projecting therethrough, a second plate removably secured with relation to said first named plate and adapted to engage the heads of said spikes, and means whereby said plates may be removably secured below the sole of a shoe. 95

2. An ice creeper embodying therein a plate, a plurality of independently removable, headed spikes projecting therethrough, a second plate pivotally mounted upon said first named plate and adjacent the edge thereof, adapted to engage the heads of said spikes, and means whereby said plates may be removably secured below the sole of a shoe. 100 105

3. An ice creeper embodying therein a plate, a plurality of independently removable, headed spikes projecting therethrough, a second plate pivotally mounted upon said first named plate and adjacent the edge thereof, adapted to engage the heads of said spikes, said last named plate corresponding 110 in configuration with said first named plate, said plate having registering openings therethrough and removable means passing through said openings adapted to hold said plates against separation, and means whereby said plates may be removably secured below the sole of a shoe. 115 120

4. An ice creeper embodying therein a plate, a plurality of independently removable, headed spikes projecting therethrough, a second plate pivotally mounted upon said first named plate and adjacent the edge thereof, adapted to engage the heads of said 125

spikes, said plates having registering slits therethrough upon opposite sides of said spikes and upon opposite sides of the shanks of said plates respectively, flexible straps 5 passing through the slits adjacent said spikes and the slits in said shanks, and adjustable takeup means whereby the ends of said straps may be adjustably secured together.

5. An ice creeper embodying therein a 10 plate, a plurality of independently removable, headed spikes projecting therethrough, a second plate pivotally mounted upon said first named plate and adjacent the edge thereof, adapted to engage the heads of said 15 spikes, said last named plate corresponding in configuration with said first named plate, said plate having registering openings therethrough and removable means passing

through said openings adapted to hold said plates against separation, said plates having 20 registering slits therethrough upon opposite sides of said spikes and upon opposite sides of the shanks of said plates respectively, flexible straps passing through the slits adjacent said spikes and the slits in said 25 shanks, and adjustable takeup means whereby the ends of said straps may be adjustably secured together.

In witness whereof I have hereunto affixed my signature, in the presence of two sub- 30 scribing witnesses, this 3rd day of April, 1920.

HARRY JUBBER.
